UNITED STATES PATENT OFFICE.

HENRY A. SOMMERMEYER, OF ELMORE, MINNESOTA, ASSIGNOR OF ONE-HALF TO
GEORGE W. OWENS, OF ELMORE, MINNESOTA.

RAILROAD-SPIKE.

1,084,372.

Specification of Letters Patent.

Patented Jan. 13, 1914.

Application filed August 23, 1913. Serial No. 786,310.

To all whom it may concern:

Be it known that I, HENRY A. SOMMERMEYER, a citizen of the United States, residing at Elmore, in the county of Faribault and State of Minnesota, have invented certain new and useful Improvements in Railroad-Spikes; and I do hereby declare the following to be a full, clear, and exact description of the invention, such as will enable others skilled in the art to which it appertains to make and use the same.

My invention relates to spikes and more particularly to the type employed in locking railroad rails to the ties and has for its object to provide a device of this character which is of simple and inexpensive construction and which will more surely and efficiently perform the functions for which it is designed, than those heretofore proposed.

To these ends my invention consists in the novel details of construction more fully hereinafter described and particularly pointed out in the claims.

Referring to the accompanying drawing forming part of this specification and in which like numerals designate like parts in all the views; Figure 1 is a perspective view of a spike made in accordance with my invention, and Fig. 2 is a sectional view of a rail and tie showing the manner in which my improved spike is employed.

1 designates the body of my improved spike which is in the form of a wedge having the perpendicular face 2 and the slanting face 3 extending throughout the length of the body 1. These two faces meet to form the edge 4 adapted to facilitate the starting of the spike into the tie.

40 The upper portion of the spike is formed into a head 5 having on its rear face a lip 6 which lip is adapted to be engaged by a claw or other tool in case it is desired to remove the spike. The forward portion of the head is formed into the holding member 7 for engaging the base flange 8 of the rail 9 and in addition thereto is provided a recess 10 into which the edge of said base flange 8 is adapted to fit when the spike has been driven home in the tie 11. A shoulder 12 is formed behind the head 5 and is adapt-

ed to receive the blunt nose of a tool when driving the spike.

From the foregoing description it will be seen that when the spike is driven into the tie, the slanting face 3 extending the entire length of the body 1, will compress the wood as indicated at 13, throughout its length, but to a greater degree opposite the recess 10 than anywhere else. It therefore follows that this compression will serve to force the spike over against the rail flange immediately the edge 4 enters the wood, and as the spike is driven home, this forcing action is increased, until the recess 10 comes opposite the flange 8, when the edge of said flange will snap into said recess and the spike be held firmly in position by means of the compressed portion 13.

A sharp distinction is to be drawn between my spike and those which provide for a wedge member extending over a portion of the length of the body, for the latter spikes do not force the body toward the flange 8 until the wedge portion is buried in the wood, and therefore their operation is uncertain. Further, the compressed portion of the wood, in such cases, does not extend throughout the body portion of the spike, and the firm, compressed, resilient backing provided by my spike, is absent.

What I claim is:—

1. A spike comprising a body portion and a head portion with a rail base locking recess between said portions; said body portion being wedge shaped throughout its length, and having an extended shoulder on its upper end for engagement with a tool in driving the spike; said head portion being provided with a lip extending over said shoulder to facilitate the withdrawal of the spike and on its opposite side with a rail base engaging member overhanging and extending beyond said rail base locking recess, substantially as described.

2. A spike comprising a body portion and a head portion with a rail base locking recess between said portions; said body portion being wedge shaped throughout its length, and having an extended shoulder on its upper end for engagement with a tool in driving the spike; said head portion being

provided with a lip partially extending over said shoulder to facilitate the withdrawal of the spike and on its opposite side with a rail base engaging member tapered on its upper and lower surfaces overhanging and extending beyond said rail base locking recess, substantially as described.

In testimony whereof I affix my signature, in presence of two witnesses.

HENRY A. SOMMERMEYER.

Witnesses:

GEO. W. OWENS,
HERMAN NELSON.
